UNITED STATES PATENT OFFICE

165,418

SEWING CABINET

A. Ivar Ekstrom, Rockford, Ill.

Application August 2, 1951, Serial No. 16,128

Term of patent 7 years

(Cl. D3—19)

To all whom it may concern:

Be it known that I, A. Ivar Ekstrom, a citizen of the United States, residing at Rockford, in the county of Winnebago and State of Illinois, have invented a new, original, and ornamental Design for a Sewing Cabinet, of which the following is a specification, reference being had to the accompanying drawings, forming part thereof.

In the drawings:

Fig. 1 is a side view of a sewing cabinet embodying my new design;

Fig. 2 is a plan view;

Fig. 3 is a front end view; and

Fig. 4 is a longitudinal section taken on the line 4—4 of Fig. 2.

I claim:

The ornamental design for a sewing cabinet, as shown.

A. IVAR EKSTROM.
